COMBINED BOTTLE AND CAP THEREFOR

Ralph Anthony Muscatiello, Norwood, Mass., assignor to
The Gillette Company, Boston, Mass.

Filed Feb. 5, 1970, Ser. No. 21,273

Term of patent 14 years

Int. Cl. D9—01

U.S. Cl. D9—144

Fig. 1

Fig. 2

Fig. 3

Fig. 4

FIG. 1 is a perspective view of a combined bottle and cap therefor showing my new design;

FIG. 2 is a front elevational view thereof;

FIG. 3 is a side elevational view thereof; and

FIG. 4 is a top plan view thereof.

The undisclosed back is substantially the same in appearance as the front.

The undisclosed side is substantially the same in appearance as the side shown.

I claim:

The ornamental design for a combined bottle and cap therefor, substantially as shown and described.
